(57) **CLAIM**

The ornamental design of a cutter for tire rim, as shown and described.

DESCRIPTION

FIG. 1 is a perspective view of a prior art tire rim; FIG. 2 is a front perspective view of a cutter for tire rim shown in its position of use, showing my new design; FIG. 3 is a rear perspective view of FIG. 2; FIG. 4 is a perspective view of a cutter for tire rim shown with a tire mounted thereon; and, FIG. 5 is a perspective view FIG. 4 shown with the tire portion partially removed.

In the drawings, the broken lines depict environmental subject matter only and form no part of the claimed design.
